UNITED STATES PATENT OFFICE.

HARRY LOEVEN, OF DOUGLAS, ARIZONA.

COMBINED CRUSHER AND MILL.

1,404,982.

Specification of Letters Patent. Patented Jan. 31, 1922.

Application filed November 16, 1920. Serial No. 424,386.

To all whom it may concern:

Be it known that I, HARRY LOEVEN, a citizen of the United States, and a resident of Douglas, in the county of Cochise and State of Arizona, have invented certain new and useful Improvements in Combined Crushers and Mills, of which the following is a specification.

My invention relates to mills, and a purpose of my invention is the provision of a combined crusher and mill which is constructed to automatically effect the return of over size ore to the mill so as to cause a reduction of the ore to the required degree of fineness in a single continuous operation.

It is also a purpose of my invention to provide a combined crusher and mill including a rotatable drum of angular contour, anvils secured to the inner wall of the drum, and slugs rotatable within the drum, the drum providing, because of its contour, pockets in its several corners in which finely milled ore accumulates at points out of reach of the slugs, while the larger ore or rock is continuously lifted by the breaker bars or anvils and precipitated onto the slugs. By virtue of this arrangement, the finely milled ore is prevented from retarding the rotation of the slugs, thus leaving the latter free to act upon the larger ore or rock in effecting a reduction of the latter to the required degree of fineness.

I will describe two forms of combined crushers and mills embodying my invention and will then point out the novel features thereof in claims.

In the accompanying drawings:

Figure 1 is a view showing in rear elevation one form of combined crusher and mill embodying my invention.

Figure 2 is a view showing in top plan the crusher and mill shown in Figure 1.

Figure 3 is a vertical longitudinal sectional view taken on the line 3—3 of Figure 4.

Figure 4 is a transverse sectional view taken on the line 4—4 of Figure 3.

Figure 5 is an enlarged detail perspective view of the removable section of the drum of the crusher and mill shown in the preceding views.

Figures 6 and 7 are detail perspective views of the slugs shown in Figure 3.

Figures 8 and 9 are views similar to Figures 3 and 4, respectively, showing a modi-

fied form of drum sections in applied position within a mill of the same construction as that shown in Figures 3 and 4.

Figure 10 is an enlarged detail perspective view of a modified form of drum section shown in Figures 8 and 9, with certain of the screens removed.

Figure 11 is a detail view showing in vertical section one of the vibrating members shown in Figure 3.

Figure 12 is a detailed perspective view of a modified form of slug adapted to be used in place of the slugs shown in Figures 6 and 7.

Similar reference characters refer to similar parts in each of the several views.

Referring specifically to the drawings and particularly to Figures 3 and 4, D designates generally the drum of the combined crusher and mill into which ore or other material is adapted to be placed and treated in effecting a reduction of the same to the required degree of fineness. As shown in Figure 3, the drum as a unit is mounted for rotation upon a plurality of flanged rollers 15 which engage annular flanges 16 formed integral with or secured to the outer sides of heads 17 and 18. The heads 18 and 17 constitute the front and rear portions of the drum D, while the body of the drum is composed of a plurality of plates P arranged and secured in the form of a rectangle with one of their ends secured to the front head 18 through the medium of ribs 19, while their opposite ends are secured to a partition 20. As shown in Figure 3, the partition 20 is arranged in spaced relation to the rear head 17 and is held in such position by bars 21 arranged in divergent relation to each other and extending radially from the axis of the drum as clearly shown in Figure 4.

The bars 21 coact with the rear head 17 and the partition 20 to provide a plurality of chutes designated at S for effecting communication between the interior of the drum and its periphery. The chutes S are subdivided by means of ribs 22 which, as shown in Figures 3 and 4, extend radially from the center of the rear head 17 with their inner ends curved inwardly along the hub of the head. The ribs 22 are designed for the purpose of effecting a uniform distribution of the ore into the drum as will be more fully described hereinafter.

As shown in Figure 4, the partition 20 is

provided at its center with an entrance opening which communicates with the several chutes S into which extend the ribs 22. This opening is surrounded by an annular guide flange 23 that is curved in the manner shown in Figure 3 so as to guide the ore into contact with the slugs in the drum as it passes through the entrance opening. It will be noted that the form of the guide flange 23 is such as to effect a similar guiding of the ore from the interior of the drum into contact with the slugs.

As shown in Figure 3, the plates P are provided with relatively large perforations and are relatively thick to withstand the force of the ore as it is thrown against the walls by rapid rotation of the slugs. These plates are provided upon their inner surfaces with breaker bars or anvils 24 which are in the form of bars that extend longitudinally of the drum, as shown. Any number of anvils 24 may be provided, the purpose thereof being to effect a lifting of rock ore during the rotation thereof so as to precipitate the ore onto the slugs.

As shown in Figure 4, the body of the drum D is surrounded by a pair of circular screens E and E', such screens being spaced apart and arranged concentrically of each other with the inner screens E supported in spaced relation to the plates P by means of brackets 25. The screens E and E' are made up of sections, each section extending from one radial bar 21 to the next bar 21. The several sections of the outer screen E' are secured at one end to an annular rib 26 secured to the front head 18, while the opposite end is secured to a similar rib 27 secured to the rear head 17. One end of the screen E is likewise secured to a rib 28 carried by the front head 18, such rib coacting with the several brackets 25 for rigidly supporting the screen as a unit in spaced relation to the plates P.

As shown in Figure 3, the screen E is formed of sheet metal which is provided with perforations having a diameter much less than the diameter of the perforations of the plates P. The screen E' is formed of wire having a mesh which will allow of the free passage of the finely divided ore therethrough.

For gaining access to the interior of the drum D for the purpose of inspecting and removing, if necessary, the parts of the mill contained therein should they become worn or broken, one section of the drum including one plate, one section of the screen E and one section of the screen E', is removable. This section of the drum is clearly shown in Figure 5 as well as in Figures 3 and 4, and as here shown it comprises a pair of plates 29, a perforated plate P interposed between the two and secured at one end to one of the

plates. The opposite end of the plate P is provided with a segmental flange 30 which is secured to guide blocks 31 carried by the other plate 29 and arranged in divergent relation thereon as is clearly shown. The space between the flange 30 and the adjacent plate 29 constitutes a portion of a corresponding chute S so that the ore between the plate P and the screens E and E' has access between the chutes in effecting a return of the same to the interior of the drum. The plates 29 have secured thereto bars 32 which constitute handles for moving the section as a unit into or out of position with respect to the drum, the section in applied position being supported by means of the plates 29 engaging the divergent bars 21, and locked into engagement with such bars by means of screws or other suitable fastening members.

As shown in Figure 5, the segmental section of the ribs 26, 27 and 28 are carried by the plates 29 for supporting the sections of the screens E and E' in proper spaced position.

As clearly shown in Figure 3, the screens E and E' are of frusto-conical form with their larger ends disposed adjacent the several chutes S so that the space between the screens, as well as the space between the screen E and the plates P are all in communication with the outer ends of the chutes. The screen E' is adapted to be vibrated so as to insure the percolation of the ore therethrough by means of a plurality of plungers designated at G and which are arranged at suitable intervals about the drum in the manner shown in Figure 3. As shown in Figure 11, each plunger G comprises a cylinder 33 having a reduced end portion which is threadedly fitted within the walls of a suitable opening formed in one of the plates P. Threadedly fitted in the opposite end of the cylinder 33 is a tubular sleeve 34. Slidably fitted within the casing 33 and the sleeve 34 is a stem 35 made up of two sections which are adjustable longitudinally with respect to each other through the medium of a threaded shank 36. The shank 36 is fixed to one of the sections of the stem 35, while the other section threadedly receives the shank so that it can be adjusted longitudinally thereon. The innermost section of the stem is provided with a head which engages the head of a plunger 37 that extends through and beyond the inner surface of the plate P. The outer end of the screw threaded shank 36 carries a nut 38 which, when rotated in the proper direction, will engage the outer section of the stem 35 to effect a longitudinal adjustment of the stem and to maintain such adjustment. A plurality of washers 39 are adapted to be placed upon the plungers 37 so that as the

latter wears, the washers can be removed to cause the desired projection of the plunger beyond the inner surface of the plate P.

In the operation of any one plunger, the ore within the drum D striking against the plunger 37 effects outward movement of the stem 35. During this movement of the stem 35 the shank 36 is caused to engage and vibrate a band 40 secured to the screen E' whereby the vibration of the latter is effected. The band serves to return the plungers to normal position after the ore has disengaged them. The adjustability of the stem 35 allows of the adjustability of the plunger 15 as a unit so that the intensity of the vibration imparted to the screen can be increased or decreased at will.

Referring again to Figure 3, it will be seen that the drum D together with the screens E and E' rotate about a common axis which in the present instance is a shaft T journaled in standards 41. The shaft T extends through an entrance opening formed in the front head 18 and through which the ore to be milled is adapted to be introduced into the drum. This entrance opening is bordered by an angular guide flange 42, which is designed for the purpose of preventing the accidental ejection of the ore from the drum through the entrance opening and for guiding the ore into engagement with the slugs. The slugs are designated at L and are here shown as fixed to the shaft T, the latter being surrounded by a projecting sleeve 43 so as to prevent the ore from injuring the shaft. As shown in Figures 6 and 7, the slugs L consist of rectangular blocks of metal that are adapted to be maintained in spaced relation upon the shaft T by means of spacing blocks 44. As shown in Figure 6, each slug L carries a block 45 which is rotatably mounted thereon by means of a rod 46, the rod 46 in the present instance extending through all of the slugs 45 and through all of the blocks. It is to be noted that the blocks are arranged adjacent one corner of the slugs so that they will coact with the slugs in effecting a disintegration of the ore. In Figure 7, I have shown a slug L provided with a block 47 which is rigidly secured to the slug. In Figure 3, a plurality of such blocks 47 are shown interposed between adjacent slugs. In this latter figure I have also shown the application of the blocks 46. Either or both can be used.

In Figure 12 I have shown another form of slug which may be used with or in place of the slug L. As here shown the slug is designated at L' and is of disc formation. Pivotaly connected to the slug is a pair of links 53 between which is rotatably mounted a wheel 54. During the rotation of the slug L', the wheel 54 is thrown out of the radial position shown and is adapted to swing about the inner ends of the links as a center

when contacting with the ore in the drum so as to effect a hammering action upon the ore.

In the operation of the drum and slugs, the former is adapted to be driven in the same direction as the slugs but at a speed less than that of the slugs. Any suitable form of driving mechanism may be provided. As shown to advantage in Figure 2, the mechanism in the present instance comprises a pulley 48 fixed to the shaft T and to which power is adapted to be applied by means of a belt 49. A pair of shafts 50 and 51 carry certain of the flanged wheels 15 and are adapted to be driven from the shaft T through the following mechanism: A pulley 52 is fixed to the shaft T adjacent the pulley 48, and trained about this pulley 52 is a belt 52^a. The belt 52^a is also trained about a pulley 52^b fixed to a shaft 52^c. Power from the shaft 52^c is conveyed to the shaft 51 through gears 52^d. The shaft 51 in turn drives the shaft 50 through the pulley and belt connection shown.

By this arrangement it will be seen that with the shaft T rotating, the slugs carried by such shaft will be rotated at a corresponding speed, while through the medium of the mechanism for driving the shafts 50 and 51, the rotation of the drum 95 is effected at a speed less than that of the slugs.

The operation of the crusher and mill just described is as follows:

With the drum and slugs rapidly rotating, ore is introduced into the drum through the entrance opening in the front head 18 and upon such introduction, the ore is carried upwardly by the anvils 24 where it is dropped onto the slugs L and the blocks 46 and 47. Upon contacting with the slugs and blocks, the ore is disintegrated and projected against the plates P, the fine ore passing through the perforations of the plates and into the space between the plates 110 and the screen E. From this point the ore passes through the screen E and ultimately through the screen E', the vibration of the latter insuring the passage of the same therethrough as had been described. That ore which is too large to percolate the screens E' is ultimately ejected from the large ends of the screens into the chutes S where it finally returns into the drum. This action is effected as a result of the frusto-conical formation of the screens, it being understood that ore is subjected to the action of the centrifugal force created by the rotation of the drum and that such force causes a longitudinal feeding of the ore in 115 the direction of the large ends of the screens.

The large or over size ore which is returned to the drum is again acted upon by the slugs, and this operation is repeated until the ore is reduced to the required degree of 130

fineness so that it will all percolate through the screens and thus exteriorly of the drum. As has been previously described, the flanges 23 and 42 serve to guide the ore into contact with the slugs, which in conjunction with the lifting action of the anvils 24 effects a complete disintegration of the ore. The anvils 24 also serve to prevent the ore from moving circumferentially of and in the same direction as the moving slugs thus allowing the latter to more frequently engage the ore, and preventing excessive wear of the interior of the drum.

By virtue of the angular formation of the drum, the finer particles of ore are caused to lodge in the several corners of the drum and out of reach of the slugs so that the latter are free to act upon the large particles of ore.

Referring now to Figures 8, 9 and 10, I have here shown a mill of a construction identical to the construction of the mill shown in the preceding views with the exception that sections of a different form are substituted for the sections comprised in the drum D. In the present instance, the drum is composed of four separate and independent sections, each section comprising a frame F of rectangular form having at its inner end a perforated plate P'. Spaced from the plate P' and from each other are a plurality of screens designated at E², E³ and E⁴, respectively. As clearly shown in Figures 8 and 9, the screens E², E³ and E⁴ are of a mesh which decreases in degree of fineness from the innermost screen to the outermost screen. One end of the plate P' and the screens E², E³ and E⁴ are spaced from the adjacent side of the frame, this space providing a passageway or chute through which the over size ore may return to the interior of the drum. This passageway is controlled by a door 55 so mounted as to occupy an open position only when the section is in an upright horizontal position. Inward swinging movement of the door is limited by means of a guard plate 56 secured to the inner side of the plate P', such guard plate also serving to prevent contact of the ore with the door and injury to the latter.

As in the first form of my invention, one of the sections is removed so as to permit access to the interior of the drum when renewing worn or broken parts. This removable section is shown in Figure 10 and is of a construction similar to the removable section shown in Figure 5, in that it includes side plates 29^a adapted to fit between the front and rear heads 17 and 18 and to be supported by the divergent bars 21. The plates 29^a carry bars 32^a while the remainder of the section is identical in construction to the stationary sections.

In the operation of the second form of

mill, the return of the over size ore is effected through the passageways at the ends of the plates and several screens, such return, however, only occurring when the corresponding section is in upright horizontal position so that the corresponding door 55 swings to open position and thus allows the ore to gravitate into the drum. With the drum rotating, it will be clear that the several sections successively discharge the over size ore into the interior of the drum that ore which has been reduced to the required degree of fineness percolating all of the several screens and where it is finally ejected from the frames of the sections. By virtue of the fact that the several screens E², E³ and E⁴ are spaced apart from the plates P' and from each other, the disintegrated ore after passing through the plates is agitated within the spaces between the plates and screens finally working its way through the screens or passing back into the drum.

It is to be particularly noted that the sections of the drum of both of the mills are interchangeable and that by employing the sections shown in Figures 8 and 9, the several chutes S are rendered inactive. In either form of crusher and mill suitable driving means (not shown) may be provided for revolving the slugs in a direction opposite to the rotation of the drum.

Although I have herein shown and described only two forms of crusher and mill embodying my invention, it is to be understood that various changes and modifications may be made herein without departing from the spirit of the invention and the spirit and scope of the appended claims.

What I claim is:

1. A combined crusher and mill comprising, a rotatable drum of angular contour and formed of foraminous material, said drum being formed at its opposite ends with entrance openings, anvils extending longitudinally within the drum, guide flanges adjacent said openings, guide flanges surrounding the openings and extending into the drum, a plurality of screens of frustoconical form surrounding said drum, chutes formed at one end of said drum to effect communication between the larger end of said screens and one of said openings, and means for rotating said screens and drum.

2. A combined crusher and mill comprising a rotatable drum formed of foraminous material, screens of various mesh surrounding said drum, and adjustable means operable by the action of ore within the drum when the latter is rotated for vibrating the outermost screen.

3. A combined crusher and mill comprising, a rotatable drum of angular contour formed of sections, each section comprising a frame, a plurality of foraminous members within the frame spaced apart from each

other and from one end of the frame to provide a passageway for effecting communication with the interior of the drum, and a hinged door for controlling said passage-way, slugs rotatable within said drum, and means for rotating said slugs and drum.

4. A combined crusher and mill comprising a rotatable drum of angular contour and composed of a plurality of separate and independent sections, each section comprising a frame, a plurality of foraminous members within the frame spaced apart from each other and from one end of the frame to provide a passageway for effecting communication with the interior of the drum, hinged doors for controlling said passage-way so mounted as to occupy an open position only when the corresponding section is in an upright horizontal position and coacting grinding elements rotatable within the drum.

5. A combined crusher and mill comprising a rotatable drum of angular contour and composed of a plurality of separate and independent sections, each section comprising a frame, a plurality of foraminous members within the frame spaced apart from each other and from one end of the frame to provide a passageway for effecting communication with the interior of the drum, hinged doors for controlling said passage-way so mounted as to occupy an open position only when the corresponding section is in an upright horizontal position, and guard-plates associated with said doors for controlling the inward swinging movement of the doors and preventing the ore within the drum from coming in contact with the doors and coacting grinding elements rotatable within the drum. 25 30 35

HARRY LOEVEN.
